Atty

UNITED STATES PATENT OFFICE.

HERMAN G. PAPE, OF NEW YORK, N. Y., ASSIGNOR TO RALPH A. SCHOENBERG, OF NEW YORK, N. Y., NOW BY JUDICIAL CHANGE OF NAME RALPH A. BELMONT.

HOUSING FOR MECHANICAL MOVEMENTS AND FASTENINGS THEREOF.

1,263,100.

Specification of Letters Patent.

Patented Apr. 16, 1918.

Application filed December 20, 1916. Serial No. 138,132.

To all whom it may concern:

Be it known that I, HERMAN G. PAPE, of New York, in the county and State of New York, have invented a new and useful 5 **Housing for Mechanical Movements and Fastenings Thereof**, of which the following is a specification.

Heretofore in housings for mechanical movements which consisted of a plurality 10 of parts, said parts were held together by fastening means which included a screw or other locking appliance extending through the housing, which screw often became alive when the mechanical movement was connected 15 to electric wires because, among other things, a strand of the cord connected to the mechanical movement would touch the screw and give a severe shock to a person standing on a damp floor and handling the device and 20 when the wires became crossed such person might even be killed.

The main object of my invention is to overcome these and other defects and a feature of my invention consists in completely 25 surrounding the mechanical movement with completely insulated portions.

Another feature consists in having the means which hold the parts of the housing together insulated at all points from the 30 mechanical movement and the wires, if the latter are used. In the preferred form of such means I use a split ring which is not only easily put on and taken off but is completely insulated at all times, so that the 35 user feels sure at all times that he will not receive a shock, and this is a very important advantage.

Another feature of my invention is provision for ready removal of the fastening 40 means which feature is not only of great utility in itself but adds to the feeling of security in handling the device because of the knowledge that that fastening is completely insulated.

Another feature of my invention is that there is no danger of the fastening slipping out or backing out, so that I avoid all danger of the housing coming off and exposing the mechanical movement.

Another feature of my invention is a support for the mechanical movement which support interlocks with the housing.

Another feature is a housing consisting of a plurality of parts, which parts have interlocking portions to prevent relative movement.

Other features will be pointed out below.

In the drawings,

Figure 1 is a central longitudinal sectional view of a device embodying my invention;

Fig. 2 is a section on line 2—2 of Fig. 1, showing the outer housing alone;

Fig. 3 is a side elevation of the switch shown in Figs. 1 and 2;

Fig. 4 is a section on line 4—4 of Fig. 3 with the interior part of the frame removed;

Fig. 5 illustrates a modification;

Fig. 6 is a section on line 6—6 of Fig. 5; and

Fig. 7 illustrates a modification described below.

My housing is longitudinally divided and is made up of two hollow sections 1 and 2 of porcelain or other suitable material and an interior part or section 3 that is inclosed and interlocked with the housing sections 1 and 2. Each section 1 and 2 is a substantially cylindrical shell made with an interior annular recess 4, the two semi-circular recesses 4 making up a pocket into which the interior section 3 fits snugly. Section 3 is substantially cylindrical in form and recessed at its ends to accommodate the parts of the switch mechanism and provide a partition 5 on which said parts are mounted. Upon its exterior the longitudinally divided housing is made with two annular grooves 6 and 7 within one of which is arranged a split spring ring 8, Figs. 1 and 5, which 85 serves to hold the two sections together. Ring 8 is formed upon its inner side and near its middle with a boss 9 fitting into a hole 10 provided in section 1, the engagement of boss 9 with hole 10 serving to hold 90 the split 11 of ring 8 away from the joints between the sections 1 and 2.

In order to hold the two sections 1 and 2 against relative movement longitudinally the section 1 is made at each side about midway 100 of its length with an integral projection 12 occupying a recess 13 provided upon the adjacent face of section 2.

The interior part 3 is pocketed by the parts 1 and 2 and also serves to prevent relative longitudinal movement of said parts.

As an example of a mechanical movement I illustrate an electric switch of the type shown in the patent to Keefe No. 967,932 dated August 23, 1910, the yoke 14 being supported by the member 3 and the fixed contacts 15 and 16 being connected by binding

posts 17 and 18 to wires 19 and 20, the entrance of which is permitted by the opening 21 formed in sections 1 and 2.

In Figs. 5 and 6 I show a modification in which the split ring 81 has its two ends hooked inwardly to enter and engage recess 22 to prevent rotation of the split ring. Adjacent to the ends of the ring and at one side thereof member 2 is formed with a beveled depression 23 appearing in Fig. 5 and dotted in Fig. 6, the function of this depression being to permit the insertion of a suitable tool such as a screw driver beneath an end portion of the split ring so that the latter may be readily and quickly removed and this is an important feature also for the reason that the user will feel assured that, on account of the complete insulation of the ring, he will not get a shock.

In Fig. 7 I show the two sections 1^a and 2^a, the plane of division being crosswise of the device, section 1^a having a projection 24 to engage recess 25 to prevent relative cross-wise movement. In this form the split rings extend longitudinally of the device.

It will be clear that with my invention the fastening means are external to the housing and completely insulated from the mechanical movement and the wires and also that the mechanical movement is completely surrounded by insulation.

It will also be clear that the hooked ends of the spring engaging the cooperating recess locate the ends of the spring so that they will not be opposite the joints between the sections 1 and 2.

What I claim is:

1. A housing for a mechanical movement comprising a plurality of parts; and an interior separable portion interlocked with said parts of the housing and adapted to support a mechanical movement.

2. A housing for a mechanical movement comprising a plurality of parts, one of which has a recess and a split ring having its ends engaging said recess to prevent rotation of said ring.

3. A housing for a mechanical movement comprising a plurality of parts; and a split ring to hold said parts together, one of said parts having a depression at one side of, but adjacent to, one end of said spring to permit ready removal of the latter.

4. A housing for a mechanical movement comprising a plurality of interlocking parts susceptible of relative sidewise movement; an interior separable portion pocketed and supported by said parts and adapted to support a mechanical movement; and means to hold said parts together.

5. A housing for a mechanical movement comprising a plurality of interlocking parts;

an interior separable portion pocketed and supported by said parts and adapted to support a mechanical movement; and a split ring to fasten said parts together.

6. A housing for a mechanical movement comprising a plurality of interlocking parts having an exterior circumferential groove; an interior separable portion pocketed and supported by said parts and adapted to support a mechanical movement; and a split ring held in said groove to fasten said parts together.

7. A housing for a mechanical movement comprising an outer housing divided longitudinally into two parts susceptible of relative sidewise movement, and an interior separable portion on which the mechanical movement is mounted, said interior portion being interlocked with the two parts of the housing so that it is held against movement relatively thereto; means for holding the two parts of the housing against relative longitudinal displacement; and means for fastening the two parts of the housing together against sidewise movement.

8. A housing for a mechanical movement comprising a plurality of parts susceptible of relative movement in a sidewise direction and in a longitudinal direction; means to hold said parts against relative movement in one of said directions; and an interior portion held in position by said parts and itself holding said parts against relative movement in the other of said directions.

9. A housing for a mechanical movement, comprising a support; a mechanical movement mounted on said support; a plurality of housing members for said support and said movement; and a split ring to hold said members in proper relation to said support.

10. A housing for a mechanical movement comprising a support; a mechanical movement mounted on said support; a plurality of housing members for said support and for said movement, said members and said support being formed to prevent relative movement between said members and said support; and a split ring to hold said members in position.

11. A housing for a mechanical movement comprising a support; a mechanical movement mounted on said support; a plurality of housing members for said support and for said movement, said members being grooved exteriorly and said members and said support being formed to prevent relative movement between said members and said support; and a split ring in said grooved exterior to hold said members in position.

HERMAN G. PAPE.
